Specification of Letters Patent.

Patented Mar. 9, 1920.

Application filed April 29, 1919. Serial No. 293,561.

To all whom it may concern:

Be it known that I, EDOUARD BRUAND, a citizen of Switzerland, residing at Villeneuve, Canton of Vaud, in the Confederation of Switzerland, have invented certain new and useful Improvements in and Relating to Compressors, of which the following is a specification.

The subject matter of the present invention is a compressor.

It is distinguished from other known compressors by the fact that a double acting piston operates inside a cylinder and in the interior of which are contained a crank of a driving crank shaft and a connecting rod connecting the crank to the piston.

Its cylinder may be provided with a single suction valve at each end. The suction valves are for instance normally operated by a cam, but are capable of operation by other means when the pressure in the compressed fluid reservoir reaches a predetermined value or the compressor has to run idly. In this case, the arrangement may have rollers rolling over a second cam and adapted to be moved around the cam, yet continuing to remain in contact therewith, so as to be capable of assuming a position in which they then act on the valves. Said rollers may be provided with spindles working in grooves in a member adapted to turn about the axis of rotation of the cam acting on the rollers.

The above arrangement may be operative automatically under the influence of the pressure of the compressed fluid. To this effect the member adapted to turn about the axis of rotation of the cam acting on the rollers is operated, by way of example, in one direction by a piston subjected to the pressure of the compressed fluid and operated by the above pressure when the latter reaches the predetermined value, and in the other direction, by suitable return springs. Furthermore this arrangement may be constructed so as to produce the opening of the suction valves during the compression stroke of the piston, this opening taking place however in such a way that there is a slight compression at the end of the stroke.

For instance the construction comprises, on the one hand, a piston serving, when subjected to the action of the compressed fluid, to actuate the means for producing the idle running of the compressor; on the other

hand, a resilient membrane subjected to the action of the compressed fluid operates a control member, whereby either the atmospheric pressure or the pressure of the compressed fluid acts on the piston. The control member, consisting of a slide valve, is connected to a lever on which are adapted to act, on one side of the axis about which said lever rotates, the resilient membrane, and on the other side a spring of adjustable tension; a piston, which is also connected to the lever, may be subjected to the action of the compressed fluid in order to compensate entirely or partially for any end pull exerted by said fluid on the slide valve.

The cylinder may be provided with automatic delivery valves, each of which may comprise two valve bodies which are arranged one in the other and act independently of one another.

The cylinder may be provided with a system of lubrication under pressure and a system for circulating cooling water around the body thereof or in the heads thereof and around the seats of the suction and delivery valves. It may be cast in one piece with a base of the compressor, which provides a space for the fluid drawn in and channels for the compressed fluid, as well as for the cooling water.

In the drawing:

Figure 1 is a side elevation of the compressor comprising my present invention.

Fig. 2 is an end elevation of the same.

Fig. 3 is a plan of the compressor.

Fig. 14 is a side elevation illustrating the parts employed for automatically operating 5 the intake valves.

Fig. 15 is an enlarged central vertical section illustrating the parts for controlling the operation of the intake valves, and

Fig. 16 is a sectional view of a modified 10 form of delivery valve.

The cylinder *a* (see Figs. 1 to 5) in this form of the invention is cast in one with a metal base *b* and is provided with two removable heads *a*¹, *a*² carrying the positively 15 operated suction or inlet valves *b*¹, *b*² and the automatic delivery valves *c*¹, *c*². In this cylinder there is a piston *d* which has two dissimilar heads *d*¹, *d*² of the same diameter connected by a member *d*³ of slightly 20 smaller diameter and having lateral openings *d*⁴, *d*⁵. Through the opening *d*⁵ passes a horizontal driving shaft *e* journaled in a bearing *e*² which is carried by the cylinder *a* and is provided externally with a driving 25 pulley, (not shown in the drawing) and with a crank *e*¹ placed inside the piston and connected by a connecting rod *f* to one of the heads *d*² thereof.

The air to be compressed enters the base *b* 30 through an inlet *h*¹, passes into the space *h*² in the base (see Figs. 4, 5, 13) and passes by the ports *h* to the suction valves *b*¹, *b*². Each of these latter has a plate *b*³ provided with a rod *b*⁴ which slides in a guide *b*⁵ fixed in an opening in the corresponding head *a*¹ or *a*². Each rod *b*⁴ carries a washer *b*⁶ against which a spring *b*⁷ acts to close the valve and also against which an operating lever *i*¹ or *i*² acts. Each lever *i*¹, *i*² is 35 pivoted at *i*³ to a bracket *j* fixed to the cover *a*¹ or *a*² and is operated, notwithstanding the action of the springs *b*⁷ by a pusher *k*¹ or *k*². (see also Figs. 6 and 7) of rectangular cross section, sliding in guides *l*¹ parallel with the axis of the cylinder *a*. Each pusher is provided at that end opposite the levers *i*¹ or *i*² with a roller *k*³ normally in contact with a cam *l* on the shaft *e*. A spring or other means (not shown) acts on the pushers to 40 maintain contact between the rollers *k*³ and the cam *l* which operates the valve *b*¹ or *b*² to open the same at the desired moment and also permits them to close again for the 45 compression stroke.

I also employ devices so constructed as to automatically produce the opening of the suction valves *b*¹, *b*² during the compression stroke when the pressure in a reservoir into which the compressed air is delivered attains a predetermined value. To this end a cam *m* (see Figs. 6, 7 and 8) is fixed on the shaft *e* behind the cam *l* and is in contact with two rollers *n* diametrically opposite each other and mounted on spindles *n*¹ 55 adapted to move in radial guides *o*¹ of a

member *o* which rocks on a bearing concentric with the shaft *e*. The faces of the cams *l*, *m* are designed in such a way that they may be included in one and the same member. When the member *o* is in the position 70 shown in Fig. 6, the rollers *n* are not in engagement with the rollers *k*³ and cannot exert any action on them, so that these rollers *k*³ merely follow one face of the cams *l*, *m*, but when the member *o* is moved to the 75 position shown in Fig. 8 in which the two guides *o*¹ are horizontal, they interpose themselves at intervals between the rollers *k*³, which are wide enough to be able to be brought into contact with them, and the cam *m* and cause the opening of the suction valves *b*¹, *b*² during the suction and compression strokes. The face of the cam *m* is nevertheless so designed that a slight compression is produced at the end of the stroke 80 for the purpose of obviating blows between the valves and the ends of the piston and to protect the joints at each change of direction of travel of the piston *d*. The opening of the suction valves during the compression 85 strokes causes a scavenging of the cylinder.

The member *o* carries an arm *o*² (see also Figs. 1, 3, 6 and 7) in which is cut a slot *o*³ for a pin *p*¹ secured to a piston *p* moving in a cylinder *q*, which by means of a pipe *r* 90 is in communication with a special apparatus for the control of the communication between cylinder *q* and the compressed air chamber and between the cylinder and the outside air.

The special apparatus (Figs. 14 and 15) comprises a base plate 20 fixed on cylinder *q* by means of two forked arms 21 and a neck 20² screwed on to the pipe *r*. Neck 20² is in constant communication with a passage 105 22¹ within a casting 22 fixed to the base plate 20 and provided with lateral ports 22³, 22⁴ leading into a cylinder 22² in the casting 22. In a cylindrical slide 23 fitted into said cylinder 22² there are provided passage ways 110 23¹ leading into a peripheral groove 23² which is adapted to register with the port holes 22³. In the lower position of slide 23 (as represented in Fig. 15) the passage ways 23¹ are closed while when in a raised position said ways are open and the groove 23² registers with the port hole 22³ so as to put the inside of cylinder *q* into communication with a passage 20⁴ made in the base plate 20 and leading into a neck 20¹ connected by 115 any suitable means with a compressed air chamber which is not shown in the drawing. When the slide 23 is raised therefore the cylinder *q* is filled with compressed air. The portholes 23³ are in constant communication with a passage 23⁵ in the slide 23 in which there are also radial ports 23⁶ by which an open passage is provided when in proper position into openings (not shown in 120 the drawing) in the casting 22 and leading 125 into a passage 23⁷ in the slide 23. The slide 23 is held in its raised position by a spring 24 which is 130

to the outside air. In the lower position of the slide 23 the cylinder q is therefore in communication with the atmosphere.

The slide 23 is connected at 24¹ to one end of a lever 24 pivoted in 24², the other end of said lever being provided with a screw 24³ bearing by means of cap 25¹ against a spring 25 located within an open cup 26 which is part of the casting 22. Normally the lifting action of the spring 25 is counterbalanced by a shank 27 movable in a guide 26¹ and supported by a block 28¹ rigidly attached to a diaphragm 28 against which the air-pressure within passage 20⁴ acts. Between the hinge 24¹ and shank 27 a rod 29 is hinged at 24⁴ to the lever 24 said rod being fast to a piston 29¹ mounted in a cylinder 22⁸ which is also a part of the casting 22. By meeting with the head 29² of the cylinder 22⁸ the piston 22¹ will stop the upward movement of slide 23. Furthermore the upper face of the piston may be subjected to the pressure of the compressed air in the passage 20⁴, due to the fact that in the upper position of slide 23 the groove 23² communicates with a port 22⁷ connected by a passage 22¹⁰ and a port 22¹¹ with the inside of cylinder 22⁸.

The operation of this apparatus is as follows:

The tension of spring 25 is regulated by means of the screw 24³ so as to counterbalance the upward pressure of the air in the passage 20⁴ on diaphragm 28 when there is a predetermined pressure in the compressed air reservoir.

As long as the air-pressure is below the predetermined pressure the different parts of the apparatus will be in the position as indicated in Figs. 14 and 15. The shank 27 and the diaphragm 28 are maintained in their downward positions by the end member 28¹ and the opposite end of the shank being at some distance from lever 24 does not act on the same. The spring 25 will therefore be free to exert all its energy to cause the slide 23 to be pressed against the bottom of cylinder 22² notwithstanding the action of the compressed air within passage 20⁴ which acts only against a small surface of said slide. Therefore the inside of cylinder q will communicate normally with the atmosphere through the parts r , 20², 22¹, 22⁴, 23³, 23⁵, 23⁶. Springs s acting on pin p^1 maintain the piston p in the position indicated in Fig. 6 and the rollers n are in their position of rest; that is when the compressor is running normally.

At the moment when the pressure of the reservoir and within the passage 20⁴ reaches the predetermined value the diaphragm 28 rises and carries the shank 27 into contact with the lever 24, but the pressure thus exerted against the lever by the shank is substantially the same as that exerted by

the spring 25 and consequently the lever 24 will not be moved.

If the pressure exceeds the predetermined value the pressure on the diaphragm 28 will be greater than that of spring 25 and the lever 24 will move to compress the spring and raise the slide 23. After the initial upward movement of the slide 23 the air from passage 20⁴ acts on a greater surface of the slide and assists the rising movement. As a result of this movement the groove 23² reaches the ports 22³ and 22⁷. When the port 22³ is uncovered the interior of cylinder q is put into communication with the compressed air vessel, and the piston p is moved from right to left as illustrated, and the rollers n come between cam m and rollers k^3 , so that the compressor will stop feeding the air into said vessel. When the port 22⁷ is uncovered the compressed air enters cylinder 22⁸ acting downward on the piston therein. This pressure will nearly counterbalance that against the bottom face side of slide 23 and will therefore not interfere with the sensitiveness of the apparatus.

As soon as the pressure in the compressed air-vessel falls to its normal point the spring 25 moves back the lever 24 and the slide 23 into their former positions and the connection between the compressed air vessel and the cylinder q is cut off and the latter is put into communication with the outside air so as to permit the compressed air contained therein to escape at a speed which is regulated by a needle-valve 30. The springs s will return the member o to its initial position and the compressor then runs normally again.

Regarding the air contained within the cylinder 22⁸ this eventually escapes by leaking out along piston 29¹. The various ports are arranged so that slide 23 has to travel a certain distance in passing from the position where the cylinder q communicates with the outside air to that in which it communicates with the compressed air-vessel. This is to cause the apparatus to operate without delay. Notwithstanding this it is extremely sensitive for there is but a short path between one position of the slide and the other.

Protecting stirrups 31 are provided on the axis of lever 24. Certain parts of the apparatus may be provided with holes for affixing leads the breaking of which would indicate an undue regulation of the apparatus. Between the base-plate 20 and the cylinder 22² a packing may be interposed.

The cams l , m and the member o are contained in a jacket t (see Figs. 1, 3, 6, 7) having openings for the passage of the rollers k^3 and of the arm o^2 .

Each of the delivery valves c^1 , c^2 has a plate c^3 (see Fig. 4) provided with a rod c^4 sliding in a screw-threaded plug c^5 (see

also Figs. 1 to 3) which acts as a guide and against which a return spring c^6 bears, each valve communicates by a passage in a cover u (see also Fig. 12) with a port u^2 in the base b , common to the two valves c^1 , c^2 and terminating in a suitable delivery pipe.

The compression chambers, or the two ends of the cylinder a are surrounded by water jackets w (see Figs. 1, 3, 4) in communication with the water chambers w^1 formed in the heads and surrounding the valves. The inlet and outlet of the cooling water take place by the ports w^2 and w^3 . The jackets and the chambers of the two ends are connected by the port w^4 in the base and by the port w^5 at the top of the cylindrical member.

The lubrication of the different parts of the compressor is insured by a reservoir x (see Figs. 1, 2, 3, 4, 5, 11) containing a lubricant under pressure. This latter has a container x^1 cast in one with the body of the cylinder a and a removable cover x^2 held in place by winged screw plugs y engaging with screw threaded rods z screwed into the base of the reservoir. Into this latter opens a passage 1 which starts from the left hand compression chamber and permits the desired pressure being obtained in reservoir x and this passage is provided with a pointed regulating screw 5 and a non-return valve 9 (see also Fig. 2). From the reservoir run two ports each meeting outside a glass tube 3, each glass tube 3 is connected to a passage 4 (see also Fig. 10) at each end of the cylinder a and serves for the lubrication thereof; screws 5 permit the regulation of the flow through these passages which is thus controlled on its way in the tubes 3. Another glass tube 6 permits the level of the oil in the reservoir x to be seen at any moment. Finally there is a fourth glass tube 7 which supplies the bearing e^2 , the crank pin and the large end of the connecting rod through a passage 8 and the medium of the pipe 9, connected to a passage bored in the interior of the crank shaft.

The oil in excess in the cylinder a is sent back again into the reservoir x by an oil pump 10 (see Figs. 1, 3, 6), the piston of which is mounted on the pusher k^2 . The suction side of this pump is indicated at 11 and is connected by a pipe 15 to a passage 16 (see also Fig. 4) in the bottom of the cylinder under the bearing e^2 . The discharge of the pump is indicated at 12 and is in communication by a pipe 13 with an inlet x^4 (see Fig. 1) to the reservoir. The ports d^4 in the piston which provide passage to the head f^1 of the connecting rod, prevent its closing in any of its positions the orifice of the passage 16.

One of the screw plugs y may be provided with a pressure gage 14, as shown in Figs. 1 and 2.

Bolts 17, 18 run from one end to the other of the compressor, passing through the passages u^2 , w^4 and serve the purpose of tie rods.

In consequence of the arrangement of the crank shaft e and the connecting rod f inside the piston d the compressor is double acting, but has nevertheless no stuffing box, and is relatively light because it has no piston rod, no cross-head, no slide bars, and no extension of any kind (bayonet or spoon art) for it and the bearings for the crank shaft. The frame contains the delivery passages, those for the passage of the cooling water and also the space providing passage for the air drawn in.

In order to avoid vibration arrangement may also be made for the axis of the cylinder to be comparatively low.

If the locality where the compressor is situated contains air which is sufficiently pure and very fresh, the suction valves may open directly outward instead of being connected to passages such as h ; these latter are removable for this purpose.

In order to reduce as much as possible the waste space resulting from the thickness of the seat of the delivery valves, the body of these latter may have at its center a hollowed out enlargement intended to partially fill up this space but without however hindering the passage of the compressed fluid.

If the compressor is of small power it may be advantageous to divide the cylinder into two separated parts on a through-running division-line perpendicularly to the axis of the cylinder and provided with grooves and tongues, flanges, nut-bolts and set-pins. The relatively small weight of the single pieces will make transporting the same on man's back even on high mountains much easier than a whole cylinder may be transported.

In the case of compressors with small output and therefore of small size the cylinder might be left in one piece, but have a larger stroke than in the case represented, for the same length of cylinder. To obtain this hollow parts forming parts of the cylinder might be provided above and below the axis of the cylinder in the path of the connecting-rod head, said hollows presenting curved passages in the walls of the cylinder for letting pass the head of the connecting rod.

In other cases the cylinder might present two bores of different diameter, in the larger of which would be mounted the crank shaft and the head of the connecting-rod.

According to Fig. 16, each of the automatic delivery valves presents two coaxial members 32, 33 instead of one c^3 as shown in Fig. 4. The exterior member 32 may be fitted by means of a flange 32^1 and a packing 32^2 on a seat 32^3 provided within the

end a^2 of the cylinder a . Said member is attached to a hollow rod 32^4 sliding within a plug c^5 and is subjected to the action of a spring c^6 lodged in the rod 32^4 around a rod 32^7 and bearing at one end on an open disk 32^5 located also within 32^4 and at the other end on a washer 32^8 fixed to the plug c^5 . The rod 32^7 is fitted with a piston 32^{12} moving in a cylinder 32^{13} . This member 32 is provided with a seat 32^{10} on which the second member, 33 , is pressed by a spring 36 . The member 33 is in one piece with a stem 33^1 slidably fitted into a bore 32^{11} of the rod 32^4 .

15 At the time of delivery of compressed air by the piston d the member 32 is lifted from its seat 32^3 against the action of the spring c^6 and that of the air inclosed in the upper chamber of the cylinder 32^{13} and compressed 20 by piston 32^{12} , so that the stopping of said member occurs noiselessly and without shock by a cushioning effect. As the delivery of the latter member will not suffice, the member 33 will also be lifted from its seat 32^{10} , and lifting movement is stopped noiselessly and without shock by the compression of the air inclosed within the bore 32^{11} of stem 33^1 . The springs c^6 , and 36 may be weak and will therefore cause the members 32 , 33 to be returned quietly to their seats 32^3 , 32^{10} .

It is obvious of course that the axis of the cylinder of the compressor may be vertical or inclined instead of horizontal.

35 The compressor may have more than one cylinder.

Claims.

1. In a compressor and in combination, a cylinder, a piston therein, means for operating the piston, an inlet valve, a discharge valve, cam devices for normally operating the inlet valve, and means by which under predetermined conditions the said inlet valve is opened by the said cam devices during the compression stroke of the piston.

2. In a compressor and in combination, a cylinder, a piston therein, means for operating the piston, an inlet valve, a discharge valve, cam devices for normally operating the inlet valve during the suction stroke of the piston, and means by which under predetermined conditions the said inlet valve is opened by the said cam devices during the compression stroke of the piston.

3. In a compressor and in combination, a cylinder, a piston therein, means for operating the piston, an inlet valve, a discharge valve, cam devices for operating the inlet valve during the suction stroke of the piston, and cam devices controlled by the pressure developed by the compressor by which the said inlet valve is opened during the compression stroke of the piston when the pressure has reached a predetermined point.

4. In a compressor and in combination a

cylinder and a double acting piston therein, within which piston are contained a crank of a driving shaft and a connecting rod connecting the crank to the piston, suction valves normally operated by a cam, means for operating the valves when the pressure in a compressed fluid reservoir reaches a predetermined value, said means comprising rollers rolling over a second cam and adapted to be moved around the latter cam, yet continuing to remain in contact therewith, so that they may assume a position in which the rollers act on the valves.

5. In a compressor and in combination a cylinder and a double acting piston therein, within which piston are contained a crank of a driving shaft and a connecting rod connecting the crank to the piston, suction valves normally operated by a cam, rollers rolling over a second cam and adapted to be moved around the latter cam, yet continuing to remain in contact therewith, and spindles connected to the rollers and working in a member adapted to turn about the axis of rotation of the latter cam.

6. In a compressor and in combination, a cylinder, a double acting piston therein, means for driving the piston, cylinder heads, intake valves in each of the cylinder heads, discharge valves in each of the cylinder heads, cam devices for operating the intake valves during the suction stroke of the piston, and cam devices by which the intake valves are automatically opened during the compression stroke of the piston when the pressure developed by the compressor reaches a predetermined point.

7. In a compressor and in combination a cylinder and a double acting piston therein, within which piston are contained a crank of a driving shaft and a connecting rod connecting the crank to the piston, suction valves normally operated by a cam, rollers rolling over a second cam, and adapted to be moved around the cam, yet continuing to remain in contact therewith, and a member connected to the rollers, adapted to turn about the axis of the cam and operated in one direction by a piston subjected to the pressure of the compressed fluid, in the other by one or more return springs.

8. In a compressor and in combination a cylinder and a double acting piston therein, within which piston are contained a crank of a driving shaft and a connecting rod connecting the crank to the piston, suction valves normally operated by a cam, rollers rolling over a second cam and adapted to be moved around the cam yet continuing to remain in contact therewith, a member connected to the rollers and adapted to turn about the axis of the cam, a piston operating the rollers when said piston is subjected to the pressure of the compressed fluid, and a resilient membrane also subjected to the pressure of

the compressed fluid and actuating a control member by means of which either the atmospheric pressure or the pressure of the compressed fluid acts on the piston.

5. In a compressor and in combination a cylinder and a double acting piston therein, within which piston are contained a crank of a driving shaft and a connecting rod connecting the crank to the piston, suction valves normally operated by a cam, rollers rolling over a second cam and adapted to be moved around the cam yet continuing to remain in contact therewith, a member connected to the rollers and adapted to turn about the 10 axis of the cam, a piston operating the rollers when said piston is subjected to the pressure of a compressed fluid, and a resilient membrane also subjected to the pressure of the compressed fluid, a control slide valve 15 operated by the resilient membrane and connected to a lever, on which act, on the one side of its axis of rotation, the resilient membrane, on the other side a spring of adjust- 20

able tension, and a piston, also connected to the lever and adapted to be subjected to the 25 pressure of the compressed fluid.

10. In a compressor and in combination a cylinder and a double acting piston therein, within which are contained a crank of a driving shaft and a connecting rod connecting the crank to the piston, suction valves normally operated by a cam, and means for also operating said valves when the pressure in a compressed fluid reservoir reaches a predetermined value, said means being so 30 arranged that they produce the opening of the suction valves during the delivery stroke of the piston, this opening taking place however in such a way that there is a small compression at the end of the stroke. 35

40 In testimony whereof I have affixed my signature in presence of two witnesses.
